UNITED STATES PATENT OFFICE.

ROBERT O. BRITAIN, OF BOSTON, MASSACHUSETTS.

ILLUMINATED SIGN.

1,157,672.

Specification of Letters Patent. Patented Oct. 26, 1915.

Application filed January 9, 1914. Serial No. 811,190.

To all whom it may concern:

Be it known that I, ROBERT O. BRITAIN, a citizen of the United States, residing at Boston, in the county of Suffolk and State of Massachusetts, have invented a new and useful Improvement in Illuminated Signs, of which the following is a specification.

My invention relates to signs usually illuminated by electric lights, and particularly to that class in which it is intended to produce the effect of rapidly moving figures in brilliant light upon a darkened or black background.

The objects of my invention are: first, to produce the effects desired in an illuminated sign without the use of a large number of lamps; second, to save a large amount of the usual wiring for such lamps; third, to avoid the use of complicated switches; fourth, to so design and construct the mechanism that it may be operated by a small electric motor, and fifth, that the mechanism shall be of such simple design and construction as to be very simple and economical in its first cost and its subsequent operation.

Heretofore signs of this character have been constructed with a large number of lamps disposed in straight or curved lines, the wires from each lamp or group of lamps running to a switch mechanism by the operation of which the current for these lamps or groups of lamps was turned on or off successively as required, thus producing the effect of a rapidly moving body, as a serpent.

The large number of wires and the operations of the switch mechanism caused great expense in the initial cost of the apparatus and subsequent waste of electric current in proportion to the effects produced. In my device I eliminate the switch mechanism entirely and also a very large proportion of the wiring, and so produce the desired effects in a much more simple and economical manner. These results are all accomplished by means of the mechanism illustrated in the accompanying drawings, in which—

Figure 1 is a front elevation of my illuminated sign; Fig. 2 is a rear elevation with the back removed so as to show the mechanism; and Fig. 3 is a plan view, showing the outer casing in section on the lines *w*, *w*, Figs. 1 and 2.

Similar reference letters refer to similar parts in the several views.

The device as usually constructed consists

of a rectangular box A, of sheet metal, and a series of small holes *a*, *a*, in serpentine, or any other form desired, through the front, as shown in Fig. 1.

An electric motor B is suspended by the downwardly projecting brackets C, C. The motor B, is constructed in the usual manner, giving a very slow rotation to the shaft *c*, upon which is fixed the spur pinion D, 65 which engages the idle gear E. This gear transmits motion to the first gear F, of a series of like gears G, H, J, etc. All of the series of gears commencing with F, are of the same diameter and each has a radial slot 70 *f*, cut in it. They are so timed in their rotation the slot in one gear will always meet the slot in its fellow, as shown at *g*, Fig. 2. It will be understood that in all cases the teeth of all the gears are cut entirely around the periphery. All the gears are pivoted or journaled upon screws, bolts or studs fixed in the front of the sign box and rest closely against its inner side, as shown in Fig. 3.

Two electric lamps K, K, illuminate the interior of the sign box A. The electric wires L, Fig. 2, carry the current to the motor B and the lamps K, K.

The operation of my device is as follows: The motor having been started, all gears 85 revolve in direction of the arrows. As the slot *f*, of gear F, passes over the holes *a*, in the front of the sign box, light from the lamps is permitted to pass through them in succession, giving to the eye the impression 90 of moving light. The slot *f*, meeting that in the gear G, (revolving in the opposite direction), carries the succession of light partly around the gear when it is, in turn, taken up by the next gear, and so on to the 95 end of the series. As a new succession of lighted holes commences at each revolution of the gear F, it follows that a number of these serpentine light effects successively follow each other the entire length of the 100 sign.

In laying out the line of holes it is not necessary that they follow the curves or are kept near the periphery of the gears. They may vary to any extent so they do not extend beyond the limits of the slot in the gears. This is shown at *h*, and *j*, Fig. 1.

More than one slot may be cut in each gear, or in some of the gears.

Gears may be of varying diameters if the proportions are as two to one, three to one, etc., and the larger gears have a number of

slots proportionate to their relative diameters, as shown above at *m*, Fig. 2.

The electric lights used may show white or colored lights, either or both.

- 5 In the drawing a complete sign is shown, but this may be only one of a number of sections placed in any relative position to each other; or the form may be other than rectangular according to the space which 10 it is to cover or fit into.

Having described and illustrated my invention and pointed out wherein it is an improvement upon the devices at present in use I claim:

- 15 1. In an illuminated sign of the character described, the combination of a closed receptacle of opaque material whose front is pierced with a multiplicity of small holes for the passage of light, means for illuminating the interior of said receptacle, a multiplicity of toothed gears pivoted to the rear face of said front, meshing with each other in a continuous train, said gears having radial slots extending from near the 20 center to the periphery, means for rotating said gears, said holes being arranged in 25

alinement with the paths described by said slots when said gears are rotated, whereby the light from said illuminating means is alternately permitted to pass through each 30 hole and shut off therefrom, during the rotation of said gears.

2. In an illuminated sign of the character described, the combination of a closed receptacle of opaque material having in its 35 front a series of holes placed closely together along a curved line, a multiplicity of opaque gears pivoted to the rear side of said front, engaging with each other in a continuous train, said gears having radial 40 slots, means for rotating said gears, said holes being arranged in alinement with the paths described by said slots when said gears are rotated, whereby the light from said illuminating means is alternately permitted to pass through each hole and shut off therefrom, during the rotation of said 45 gears.

ROBERT O. BRITTAIIN.
